COMBINED RECESSED JAR AND FOOD PACKET

Robert H. Kries, Fullerton, Calif., assignor to Hunt-Wesson Foods, Inc., Fullerton, Calif.

Filed Aug. 4, 1971, Ser. No. 169,159

Term of patent 14 years

Int. Cl. D9—01

U.S. Cl. D9—10

FIG. 1.

FIG. 2.

FIG. 3.

FIG. 4.

FIG. 5.

FIG. 1 is a perspective view of a combined recessed jar and food packet showing my new design;

FIG. 2 is a side elevational view thereof;

FIG. 3 is a top plan view thereof;

FIG. 4 is a vertical section through the center of the jar; and

FIG. 5 is a sectional view of the jar on line 5-5 of FIG. 4.

I claim:

The ornamental design for a combined recessed jar and food packet, as shown.
